UNITED STATES PATENT OFFICE

MATHIAS REISERT, OF BROOKLYN, NEW YORK, ASSIGNOR, BY DIRECT AND MESNE ASSIGNMENTS, OF ONE-HALF TO CYPRESS NOVELTY CORPORATION, OF BROOKLYN, NEW YORK, A CORPORATION OF NEW YORK, AND ONE-HALF TO N. D. Q. SPECIALTY CORPORATION, A CORPORATION OF NEW YORK

COMBINATION PACKAGE

Application filed August 11, 1928. Serial No. 299,068.

The main object of my invention is to provide a compact, simple, and attractive package for shipping, displaying, and selling ornamental candles and candle holders. 5 Such holders usually comprise an ornamental body provided with a socket for receiving the candle and a stem for mounting the candle in a birthday cake or the like. It has been customary in the past to sell these candles and candle holders separately or in separate packages, that is, the candles are sold in packages of one-half dozen or more and the candle holders are sold either separately or in packages or boxes containing a number of 10 candle holders but not candles. In order to facilitate the display and sale of these devices I have produced a package in which both the candles and candle holders can be conveniently packed and displayed simultaneously. 15 This also facilitates the arranging of the colors of the candles and candle holders according to any predetermined color scheme and it also insures the sale of candles and candle holders of the proper size so that the candles will fit the candle holders.

According to my invention I provide a combination package consisting of a box containing a carrier so proportioned and arranged as in effect to provide three compartments. The candles are displayed in the central compartment and the candle holders are mounted in the sides of the carrier and the cover is preferably provided with a slot through which the contents can be seen.

35 Fig. 1 is a perspective view of a package embodying my invention the cover being open so as to display the contents.

Fig. 2 is a transverse sectional view with the cover closed.

40 Fig. 3 is a perspective view of the two parts of the carrier separated from each other.

Fig. 4 is a perspective view of the carrier showing the candles in place and with one candle holder omitted and another candle holder about to be inserted or withdrawn as the case may be.

45 The box is preferably formed of paste-board and may be of any suitable construc-

tion and preferably provided with a hinging cover or flap 6.

The carrier 7 supports the candles 8 and the candle holders 9 and is preferably removable from the box.

55 The carrier has a platform portion 10 which is provided with bent-down end portions 11 which serve as legs to support the platform within the walls of the carrier and leave sufficient space above the platform to 30 accommodate the desired number of candles. The body of the carrier may be also formed of paste-board and have its ends 12 overlapped and secured together, if desired.

5 The usual candle holders are provided with 35 wire stems 13 which are adapted to be inserted in the cake on which the candles are to be displayed or which stems may be bent to secure them to a Christmas tree or other support. The carrier is provided with a 70 number of openings 14 along the opposite sides adapted to accommodate the stems of these candle holders below the platform 10.

75 The candles and candle holders may be assembled in the carrier as shown in Fig. 4 and the carrier set into the box as shown in Fig. 1. This carrier being located at the center of the box walls off side compartments 15 in which the bodies of the candle holders are protected while the stems of the candle holders overlap each other in the compartment 16 beneath the platform 10 which supports the candles.

80 The box is preferably provided with side flaps 17 which give additional protection to 35 the bodies of the candle holders and cover the compartments 15—15. The cover 6 is also preferably provided with a flap 18 which is adapted to fit in between the end of the carrier 7 and the adjacent wall of the box so as 90 to hold the cover closed.

85 The cover is also preferably provided with an opening or slot 19 arranged in line with the contents so that the same may be seen without opening the box thus avoiding the 95 necessity of handling the contents for the purpose of observing the color, size, etc. of the candles. This method of packaging is particularly important in connection with articles of the character set forth since the 100

bodies of the candle holders are usually formed of icing which is comparatively fragile. The packages are cheap to make and easy to pack and are compact and attractive and at the same time afford a maximum protection of the contents and facilitate distribution, display, and sale.

5 I claim:

- 10 1. A combination package comprising a box containing a carrier, said carrier comprising side walls and a candle tray, said walls being perforated to receive the stems of candle holders and said tray affording a support for candles and a support for overhung candle holders having their stems received within the wall perforations.
- 15 2. A combination package comprising a box having a bottom, walls, and a cover, and a carrier mounted in the box, a candle tray within the carrier, said carrier being spaced from at least one side of the box and provided with means intermediate the cover and bottom to receive a plurality of stems, each stem and said carrier constituting a cantilever support for a fragile bulbous article to one side of the carrier for keeping the weight of said articles off the bottom or cover of said box.
- 20 3. A combination package comprising a box having a bottom, walls, and a cover, and a carrier mounted in the box, a candle tray within the carrier said carrier being spaced from opposite walls of the box on at least two sides and on each of said sides being provided with means intermediate the cover and bottom to receive a plurality of stems, each stem and said carrier constituting a cantilever support for a fragile bulbous article on the side of the carrier for keeping the weight of said articles off the bottom or cover of the box.
- 25 4. A combination package comprising a box having a bottom, walls, and a cover, and a carrier mounted in the box, a candle tray within the carrier, said carrier being spaced from at least one side of the box and provided with means intermediate the cover and bottom to receive a plurality of stems, each stem and said carrier constituting a cantilever support for a fragile bulbous article to one side of the carrier for keeping the weight of said articles off the bottom or cover of said box, said cantilever supporting means being constructed to limit the inward movement of said stems, to an amount sufficient to maintain the fragile articles out of contact with said carrier.

MATHIAS REISERT.
